[57] CLAIM

The ornamental design for a combined ceiling fan and light kit, as shown and described.

DESCRIPTION

FIG. 1 is a side, bottom perspective view of a combined ceiling fan and light kit showing my new design;

FIG. 2 is a front elevational view thereof;

FIG. 3 is a left-side elevational view thereof;

FIG. 4 is a rear elevational view thereof;

FIG. 5 is right-side elevational thereof;

FIG. 6 is a bottom plan view thereof; and,

FIG. 7 is a top plan view of the ceiling fan.

The broken line showing of environmental structure in FIGS. 1 and 2 is for illustrative purposes only and forms no part of the claimed design.
